UNITED STATES PATENT OFFICE.

GEORGE W. SMITH, OF CHICAGO, ILLINOIS.

PAD-SUPPORTING STAND.

1,379,132.

Specification of Letters Patent. Patented May 24, 1921.

Application filed May 28, 1918. Serial No. 237,128.

To all whom it may concern:

Be it known that I, GEORGE W. SMITH, a citizen of the United States, residing at Chicago, in the county of Cook and State of Illinois, have invented new and useful Improvements in Pad-Supporting Stands, of which the following is a specification.

This invention relates to stands for supporting a block or tablet of calendar leaves so as to permit the top leaves to be successively turned back to display the next leaf. The invention has reference more particularly to the support or holder for the leaves, and its object is to provide a novel and improved support of simple and inexpensive construction, and one which enables the block or tablet to be easily mounted in place or removed for renewal.

The object stated is attained by means of a combination and arrangement of parts to be hereinafter described and claimed, and in order that the same may be better understood, reference is had to the accompanying drawing forming a part of this specification.

In the drawing,

Figure 1 is a perspective view of the device;

Fig. 2 is a longitudinal section thereof, and

Fig. 3 is a plan view of a fragment of the base of the device.

Referring specifically to the drawing, 5 denotes a base plate dimensioned to hold the block or tablet 6 of calendar leaves, which latter are adapted to be successively turned over to display the face of the next leaf. The leaves are strung on a holder composed of a pair of loops 7 passing through slits 40 in the leaves adjacent to the top edges thereof. These loops extend upward from the base, and the calendar leaves are slideable from one side of the loops to the other for the purpose stated.

The loops 7 are resilient strips having apertures 8 at their ends to slip over lugs 9 formed at the ends of recesses 10 in the base plate 5, these lugs being opposite and

spaced. The resiliency of the strips serves to retain the same on the lugs, and as they 50 have a normal tendency to spread, their ends which are hooked over the lugs are securely held by the latter, and the loops are kept in upright position to properly support the calendar leaves. At the same time, 55 the loops can be readily detached from the lugs and removed for renewal of the calendar leaves, removal being effected by contracting the loops, whereupon their apertured ends slip off the lugs. 60

On top of the base plate 5, beneath the block 6, and inside the loops 7, seats a removable spreader plate 11 which serves to hold the loops spread, preventing accidental contraction thereof. The base plate also 65 has upstanding marginal flanges 12 at its sides which are slightly higher than the loops 7 alongside the same to serve as guards, preventing heavy objects falling thereon and dislodging the same. 70

The base plate 5 is provided with bottom bosses 13 to prevent scratching or marring of the table top or other place on which the stand seats.

The edges of the plate 11 are notched as 75 shown at 11^a, these notches providing seats for the loops to obtain a better hold.

I claim:

A device of the character described comprising a base plate having a transverse recess at the opposite longitudinal edges of which are inturned lugs, a pair of laterally spaced looped resilient strips extending upwardly from the base and detachably connected thereto at their free ends, said ends 80 extending into the aforesaid recess to seat against the opposite longitudinal edges thereof, and having apertures into which the aforesaid lugs extend, and a spreader plate seating on the base plate over the recess and positioned between the apertured ends of the looped strips for holding the same spread and impaled on the lugs. 85

In testimony whereof I affix my signature.

GEORGE W. SMITH.
